UNITED STATES PATENT OFFICE

WILLIAM F. MONTEITH, OF SALMON ARM, BRITISH COLUMBIA, CANADA

WIRE FASTENER

Application filed January 18, 1927. Serial No. 161,889.

This invention relates to securing elements and more particularly to a securing element especially adapted for use in attaching wires or the like and intended to replace the ordinary staple.

5 An important object of the invention is to provide a device of this character which may be readily applied to the wire and which, when in applied position, provides a broad contact with the wire, securely holding the same in position.

10 A further object of the invention is to provide a device of this character which may be very readily and cheaply manufactured and which will be durable and efficient in service.

15 A further object of the invention is to provide a device of this character which may be readily withdrawn from the material in which it is embedded.

20 These and other objects I attain by the construction shown in the accompanying drawings, wherein for the purpose of illustration is shown a preferred embodiment of my invention and wherein:

25 Figure 1 is a view partially in section showing a securing element constructed in accordance with my invention applied to secure a wire to a post;

Figure 2 is a front elevation thereof;

30 Figure 3 is a perspective of the nail element;

Figure 4 is a perspective of the keeper element.

Referring now more particularly to the 35 drawings, the securing element is formed in two sections 10 and 11, hereinafter referred to as the keeper element and nail element respectively. The keeper element 10 is in the form of an angle, the arms 12 and 13 of which 40 are substantially at right angles to one another. The arm 12 has formed therein a rectangular opening 14 for the passage of the nail which is rectangular in cross section to fit the opening 14, while the arm 13 tapers

45 to a point 15 adapted to enter the material to which the element is to be secured. The nail element 10 comprises a body 16 tapering longitudinally to provide a point 17 at one end thereof. The opposite end of the body is 50 provided with an integrally formed head 18

providing an inwardly facing shoulder 19 at one side of the body. The body 16 at this point of connection with the head is preferably of the same size and shape as the opening 14 through which it passes.

55 In applying the device, the keeper element is placed upon the nail and pushed back until it engages beneath the head. This places the arm 13 of the keeper element in opposition to the body 16 of the nail and the wire is engaged between these two elements and the nail driven in until both the nail and keeper element have been embedded in the material to which they are being applied to the greatest possible extent. It will be noted that 60 the element which is being secured will serve to maintain the arm 12 of the keeper element spaced from the surface to which it is attached, so that at any time, a claw hammer may be engaged beneath the flange formed 65 by the keeper to simultaneously withdraw both the keeper and nail. It will also be noted that both the keeper and nail are of uniform thickness and may thus be produced by striking the same from sheet metal of the 70 proper kind.

75 It is pointed out that since the head 18 projects only to one side of the nail and the opening 14 in which the nail fits extends longitudinally of the arm 12, this head can only be applied to overlie the free or attached end of the arm 12, as application of the nail in such manner that the shoulder 19 overlies the free end of the body will render application of the staple extremely difficult. It will follow that 80 this head will be positioned to overlie the attached end of the body. In this way, the strain is applied more nearly against the pointed end or arm of the keeper and the shoulder overlies the wire W or other element 85 which is being secured, so that there is no tendency to deflect the free end of the arm 12 downwardly and render insertion of the claws of a hammer difficult.

90 Since the construction hereinbefore set forth is capable of a certain range of change and modification without materially departing from the spirit of the invention, I do not limit myself to such specific structure except as hereinafter claimed.

I claim:—

1. A securing element comprising a relatively thin, flat nail having a head of the same thickness as the body, the head projecting in one direction in the plane of the nail to form an inwardly facing shoulder, and an angular keeper, the arms of which are disposed substantially at right angles, one of said arms being sharpened, the other arm having a rectangular passage through which the nail passes and which the nail fits, the head of the nail projecting laterally from the body of the nail a distance approximately equal to the distance between the aperture in the keeper and the point of junction between the arms whereby the sharpened end of the keeper may be forced for a considerable distance into the material into which the nail is being driven.
2. A securing element comprising a keeper, and a nail, the nail being relatively thin and flat and being formed at its outer end with a head having the same thickness as the body of the nail, this head projecting laterally in one direction from the body of the nail to form an inwardly facing shoulder, the keeper being angular in form to provide two arms at right angles to each other, one of said arms being sharpened and in use extending approximately parallel to the nail, the other arm having a rectangular passage for the body of the nail, the passage fitting the nail snugly and having a width approximately the same as the width of the nail, the distance between the junction of the two arms of the keeper and the adjacent end of the passage being approximately equal to the depth of said inwardly facing shoulder on the nail head, the apertured arm of the keeper being transversely and longitudinally flat throughout its entire extent.

In testimony whereof I hereunto affix my signature.

WILLIAM F. MONTEITH.
